UNITED STATES PATENT OFFICE.

HENRY W. SHARPLESS, OF PHILADELPHIA, PENNSYLVANIA.

STORE-SERVICE APPARATUS.

SPECIFICATION forming part of Letters Patent No. 295,442, dated March 18, 1884.

Application filed July 21, 1883. (No model.)

To all whom it may concern:

Be it known that I, HENRY W. SHARPLESS, a citizen of the United States, and a resident of Philadelphia, in the county of Philadelphia and State of Pennsylvania, have invented 5 certain new and useful Improvements in Store-Service Apparatus, of which the following is a specification.

My invention has for its object to facilitate 10 sales operations in stores, especially in those stores in which store cash apparatus is used; and my invention consists in combining with the usual counters and shelving certain elevated desks or stations so arranged that the 15 occupants shall be readily accessible to the salesmen to receive and deliver bundles without the interposition of third parties, and so that the packing and delivery operations can be carried on without any loss of floor-space 20 usually required for packing-desks.

In the drawings, Figure 1 is a side elevation 25 of sufficient width of a counter, shelving, and packing-desk of a store to illustrate my invention. Fig. 2 is a plan view, showing a line of shelving, desk, and counters. Fig. 3 is a detached view, showing a movable packing-desk.

My invention is used in connection with 30 any of the usual arrangements of counters and shelving, which do not require to be altered in any way in order to utilize my improvements.

Heretofore it has been common to provide 35 stores with what are known as "packing-desks" at one or more localities in each store, where clerks are stationed to whom the goods are delivered, and by whom they are inspected, compared with sales-tickets, &c., and wrapped up prior to returning to the salesman and delivery to the customer. Such packing-desks 40 occupy a considerable amount of floor-space which might otherwise be made available for other purposes, and being at a distance from the greater portion of the salesmen, necessitates the employment of large numbers of 45 cash-boys to carry the goods and bundles back and forth. There are also other desks and stations, the presence of which on the floor is objectionable. To avoid these difficulties, I 50 dispense with the usual packing and other stations upon the floor of the store, and in place thereof I provide stations upon the shelving at the rear of the counters, within easy 55 reach of the salesmen, upon one, both, or all sides of said shelving, so that the goods and

tickets may be handed by each salesman directly to the packing-clerk, who wraps the same up and hands it down to the salesman. When cash-carriers are used, the various checks and tickets employed may be handed to and 60 from the packing-clerk with but little delay.

In Figs. 1 and 2, A indicates the line of shelving or cases, supporting one or more packing-desks, B, situated at any suitable point or points. C represents the counters, between 65 which and the cases stand the salesmen, who can easily pass to the wrapping-desk to hand up or receive the goods, and when cash-service apparatus is used, as indicated in Fig. 1, the ball-receiving station may be in proximity 70 to the packing-desk.

In some instances it is desirable to change the packers' positions, for which purpose I mount the packing-desk upon a case provided with wheels, so that it may be moved from 75 place to place as required.

I do not here claim, broadly, a packer's desk arranged in a position away from the floor, as this forms the subject of a separate application filed February 1, 1884; neither do 80 I claim a set of shelves with a gallery above the same, or with a station or desk thereon constituting a station for a store-service apparatus, my invention being limited to the combination, with the shelving, of a packing-desk, whereby the space on the floor occupied 85 by the shelving is also rendered available for packing purposes.

Without limiting myself to the precise construction and arrangement of parts described, 90 I claim—

1. The combination, with the counters and cases of a store, of stations for the receiving and packing clerks, arranged above and supported by the cases and accessible from the 95 salesmen's stations, substantially as specified.

2. A store provided with packing-stations arranged above and supported by the cases, substantially as and for the purpose set forth.

3. The combination, with the counters of a 100 store, of a movable case and packing desk or station above and supported thereby, for the purpose specified.

In testimony whereof I have signed my name to this specification in the presence of two sub- 105 scribing witnesses.

H. W. SHARPLESS.
